UNITED STATES PATENT OFFICE

152,128

DESIGN FOR A DOLL

Florence B. Salter, New Orleans, La.

Application April 9, 1947, Serial No. 138,257

Term of patent 3½ years

(Cl. D34—4)

To all whom it may concern:

Be it known that I, Florence B. Salter, a citizen of the United States, residing at New Orleans, in the Parish of Orleans and State of Louisiana, have invented a new, original, and ornamental Design for a Doll, of which the following is a specification, reference being had to the accompanying drawing, forming part thereof.

I claim:

The ornamental design for a doll, as shown.

FLORENCE B. SALTER.
